UNITED STATES PATENT OFFICE.

ALBERT G. JENNINGS, OF NEW YORK, N. Y.

DESIGN FOR OPEN-MESH FABRIC.

41,919.

Specification for Design.

Patented Nov. 7, 1911.

Application filed April 21, 1911. Serial No. 622,628. Term of patent 7 years.

To all whom it may concern:

Be it known that I, ALBERT G. JENNINGS, a citizen of the United States, and a resident of the city of New York, borough of Manhattan, in the county and State of New York, have invented a new, original, and ornamental Design for Open-Mesh Fabric, of which the following is a specification, reference being had to the accompanying drawing, forming part thereof.

The figure is a view of a fragment of fabric arranged in accordance with the present design.

I claim:

The ornamental design for an open-mesh fabric, as shown.

ALBERT G. JENNINGS.
